UNITED STATES PATENT OFFICE

2,630,363

DRAWER

Elmer C. Hake, Morrow, Ohio, assignor to Snap-On Drawer Company, Morrow, Ohio, a corporation of Ohio

Application November 2, 1950, Serial No. 193,631

2 Claims. (Cl. 312—320)

1

This invention relates to drawers, and more particularly, to drawers comprising a sliding skeleton frame and a disposable receptacle, and to skeleton type slide drawers per se which are designed to support disposable article-containing receptacles therein.

An object of this invention is to provide a drawer comprising a disposable receptacle and a skeleton type frame upon which the receptacle is supported and retained, the receptacle being removable when the contents have been consumed and replacable by another full receptacle.

Another object of the invention is to provide a skeleton drawer upon which may be mounted one or more receptacles such as paper boxes, containing articles such as paper clips, small screws and the like, the box or boxes serving or functioning as a part of the drawer assembly until the boxes have been emptied of their contents. When empty, the empty boxes can be refilled or replaced with full ones.

Other objects of the invention will in part be apparent and will in part be obvious from the following description taken in conjunction with the accompanying drawings in which:

Figure 1 is a view in perspective of a drawer assembly comprising a disposable receptacle and a skeleton type frame by means of which the drawer assembly may be moved to or from open position in a drawer housing or shell;

Figure 2 is a top plan view of the skeleton type drawer frame shown in Fig. 1, the frame being made from wire;

Fig. 3 is a view in section, taken on line III—III of Figure 1;

Fig. 4 is a view in perspective of a skeleton type drawer embodying a modified form of the invention;

Fig. 5 is a view in section taken on line V—V of Fig. 4; and

Fig. 6 is a view in perspective of a sectional cabinet assembly provided with a drawer of the form shown in Figs. 1, 2, and 3.

In the drawing and particularly with reference to Figs. 1, 2, and 3, a drawer assembly is illustrated as comprising a skeleton type frame 1 on which is supported and retained a disposable receptacle 2. The disposable receptacle 2 may, for example, be the original box or carton in which small articles such as paper clips, screws, nuts, et cetera, are sold. The receptacle with its contents is placed on the skeleton drawer frame as shown, the usual cover of the box having been removed so as to leave the receptacle open at the top when mounted on the drawer frame.

2

The form of drawer frame illustrated in Figs. 1, 2, and 3, is made of wire stock. A single piece of wire may be used and bent to the shape shown. When formed, the drawer frame comprises a base having at the front and rear sections thereof, legs 3 and 4, and 5 and 6, respectively, arranged to form facing V's. Adjacent legs of the V's are connected by portions 7 and 8 disposed in planes that are parallel to each other. Receptacle 2 is supported on the legs 3, 4 and 5, 6. The connecting portions 7 and 8 may be bent upwardly and shaped like inverted V's as shown more particularly in Figs. 1 and 3. Sections 7 and 8 function as side flanges to retain receptacle 2 on the frame and restrain it against lateral displacement thereon. At the front and rear ends of the frame, the wire is bent upwardly as at 10 and 11 to provide front and rear flanges which restrain receptacle 2 against endwise displacement. The top of flange 10 may be formed with a hook 12, that serves as a finger pull for the drawer.

In Fig. 4 a modified form of skeleton drawer 13 is illustrated. This form may be made of metal or of plastic that is molded to the shape shown. Drawer 13 comprises a rectangular frame having horizontally disposed side flanges 14 and 15, and end flanges 16 and 17, upon which one or more receptacles may be mounted, as indicated by the dot-dash lines. Since the bottom of the drawer frame need not be a solid panel, the area within these flanges may be open as shown. The frame includes upwardly extending side flanges 18 and 19, and front and rear flanges 20 and 21, respectively. These flanges retain disposable receptacles on the frame when in use.

The rear flange 21 is made higher than the front flange 20 to provide ample bearing support for the receptacles as the drawers are moved into or out of a housing. The front flange 20 is made short in order that the receptacle may be viewed from the front of a drawer cabinet when the drawer is closed, thereby enabling one to know from the legends on the receptacle what type of article is contained therein. The front flange 20 may be provided with a finger pull 22, which may be formed as an integral part of the drawer frame.

In Fig. 6 is illustrated a sectional cabinet comprising drawer shells or housings 25 of the type which may be secured together with interlocking fasteners as disclosed in my Patent No. 2,482,174, granted September 20, 1949. A drawer of the form illustrated in Figs. 1, 2, and 3, is shown mounted in drawer shells or housings 25 in order

to illustrate the function and utility thereof. It will be evident from inspection of Fig. 6, that the drawer frame shown in Figs. 4 and 5 may be utilized in the same manner with the same type of drawer shell or housing, or with other types of drawer housings. Drawer frames, such as shown, require only small amounts of materials in the manufacture thereof. The frames are easily manufactured, and adapted for quantity production at low cost. Drawers of the type illustrated have great utility, particularly in businesses or establishments where many and varied types of small parts are used.

Having thus described the invention it will be apparent to those skilled in this particular art, that the illustrated embodiments of the invention admit of modification without departing from either the spirit or the scope of the invention.

Therefore, what is claimed as new and desired to be secured by Letters Patent is:

1. A skeleton sliding drawer adapted to support a disposable container in a cabinet, comprising a wire frame whose front and rear end portions of the bottom are substantially V-shaped, the openings of the V's facing each other in spaced relation, adjacent end portions of said V's being

joined by an upwardly extending bent portion forming the sides of the drawer, each of said V's having at its apex an upwardly bent portion which form the ends of the drawer.

2. A skeleton sliding drawer in accordance with claim 1, characterized by the fact that the upwardly extending bent portion at the rear of the drawer is higher than the upwardly bent portion at the front of the drawer, and that the upwardly bent portion at the front end of the drawer is shaped in the form of a hook to serve as a finger pull.

ELMER C. HAKE.
